DESIGN FOR A COMBINED TOP AND BACK SPLASH PANEL FOR RANGES

Elmer D. Pellegrin, Woodstock, Ill., assignor to
Geo. D. Roper Corporation, Rockford, Ill., a
corporation of Illinois

Application March 24, 1941, Serial No. 99,802

Term of patent 14 years

To all whom it may concern:

Be it known that I, Elmer D. Pellegrin, a citizen of the United States, residing at Woodstock, in the county of McHenry and State of Illinois, have invented a new, original, and ornamental Design for a Combined Top and Back Splash Panel for Ranges, of which the following is a specification, reference being had to the accompanying drawing, forming part thereof.

In the drawing:

Fig. 1 is a perspective view of a combined top and back splash panel for ranges embodying my new design;

Fig. 2 is a front elevational view thereof;
Fig. 3 is an end elevational view thereof, and
Fig. 4 is a sectional detail on either of the lines
4—4 of Fig. 2.

The dominant features of the design reside in the portions shown in full lines.

I claim:

The ornamental design for a combined top and back splash panel for ranges, substantially as shown and described.

ELMER D. PELLEGRIN.
